(57) CLAIM

The ornamental design for a handle for car safety seat, as shown and described.

DESCRIPTION

FIG. 1 is a perspective view of a handle for car safety seat showing our new design;

FIG. 2 is a right side elevational view thereof;

FIG. 3 is a top view thereof;

FIG. 4 is a front view thereof;

FIG. 5 is a bottom view thereof;

FIG. 6 is a left side elevational view thereof;

FIG. 7 is a rear view thereof; and,

FIG. 8 is a perspective view of a handle for car safety seat thereof shown in use. The broken lines showing of the car safety seat is for illustrative purposes only and forms no part of the claimed design.
